WARNING SIGNAL DEVICES

Paul H. Griffith, Narbeth, Pa.

Application June 27, 1955, Serial No. 518,319

5 Claims. (Cl. 88—78)

This invention relates to warning signals of the reflector lens type (as distinguished from fuses or flares, or lamps) adapted to be placed, by motorists or truckers along highways in the vicinity of stalled or disabled vehicles at night, to apprise by light reflection, oncoming drivers of the emergency.

The chief aim of my invention is to provide a warning device of the kind referred to which is of simple construction and collapsible for convenience of storage in a small space in the trunk of an automobile or motor truck normally, and of which the reflector lens or lenses are so mounted and arranged as to be vibrated by prevailing wind currents or by wind currents set up by passing vehicles as beams from the head lights of approaching vehicles impinge upon them.

Other objects and attendant advantages will appear from the following detailed description of the attached drawings, wherein:

Fig. 1 is a perspective view of a warning signal device conveniently embodying my invention in one form.

Fig. 2 shows the device of Fig. 1 in front elevation.

Figs. 3 and 4 are fragmentary views in section taken as indicated respectively by the angled arrows III—III and IV—IV in Fig. 2.

Figs. 5 and 6 are perspective views of two modified embodiments of my invention.

Fig. 7 is a fragmentary view in front elevation of another modified embodiment.

Fig. 8 is a sectional view taken as indicated by the angled arrows VIII—VIII in Fig. 7.

Fig. 9 is a view similar to Fig. 7 showing another modification.

Fig. 10 is a horizontal sectional view taken as indicated by the angled arrows X—X in Fig. 9.

Fig. 11 is an elevational view which in turn, is similar to Fig. 7 and shows still another modified embodiment; and

Fig. 12 is a horizontal sectional view taken as indicated by the angled arrows XII—XII in Fig. 11.

With more specific reference first more particularly to Figs. 1—4 of these illustrations, the warning signal of my invention there exemplified, comprises a support which includes an open quadrangular frame 1 whereto is hingedly connected at the bottom corners as at 2, a U-shaped base member 3. When turned to the position of Fig. 1 the base member 3 serves to sustain the frame upright at a slight rearward inclination to the vertical, this position of the frame being determined by contact of outwardly offset lugs 5 at the sides 6 thereof with the top edges of the leg portions 7 of said base member 3. The frame 1 and the base member 3 may be fashioned from metal or other suitably stiff material. As will be readily apparent, the device can be collapsed for convenience of storage in a small space by turning the base component 3 clockwise on the hinge connections 2 about the frame 1 incident to which the lugs 5 are cleared by the edge notches 8 in the leg portions 7 of said base component. The top bar 9 and a central transverse bar

2

10 of the frame 1 have pendent ears 11 and 12 medially thereof between which pivot pins 13 and 14 extend. Freely suspended from the pivot pins 13 and 14 are lens carriers 15 and 16 in which relatively flat red discoid reflector lenses 17 and 18 are mounted respectively. These lenses may be of glass or plastic, and preferably their surfaces are either broken up, or they have incorporated grids that provide multitudinous reflecting facets of small area, as conventionally indicated in the drawings. The lens carriers 15 and 16 are provided at opposite side edges with fins 19 and 20 respectively which, in this instance, are all inclined in the same direction. In practice, at least three of the devices are intended to be set up on the highway, one adjacent the side of the stalled or disabled vehicle and one at a substantial distance from each end of such vehicle. By action of prevailing wind currents or by wind currents created by passing vehicles upon the fins 19 and 20, the lens carriers 15 and 16 are swung laterally on the pivot connections 13 and 14, and are restricted to oscillations of small amplitude by the side portions 6 of the frame 1 which act as stops as shown in dash and dot lines in Fig. 2. As the rays from the head lamps of oncoming vehicles strike the lenses 17 and 18 at night, the reflected light is broken up by the facets 25 of the lenses and, due to oscillation of the latter, a scintillating effect is created by which the effectiveness of the signal is rendered more conspicuous.

For use of the device in the day time, vertically aligned holes 21 and 22 are provided respectively in the top and 30 medial bars 9 and 10 of the frame 1 for insertion of the stem of a red warning flag (not illustrated).

The modified device illustrated in Fig. 5 is identical with the first described device, except that here, the fins 20a of the lowermost lens carrier 16a are inclined oppositely to the fins 19 of the uppermost lens carrier 15.

Accordingly the lens carrier 16a is swung, by wind action, contrariwise relative to the lens carrier 15 to render the warning even more conspicuous.

In Fig. 6, the frame component 1 of the device is devoid of a medial cross bar, and the two lenses 17 and 18 are mounted, one above the other, in a single carrying member 15b which is provided at its opposite side edges with angularly directed fins 19b. Obviously in this instance, the lenses 17 and 18 are oscillated in unison by action of wind currents upon the fins 19b.

In Figs. 7 and 8 the carriers 15c and 16c are suspended respectively from pivots 13c and 14c for capacity to swing forwardly and rearwardly within the frame 1 and are provided at their bottoms, as instanced at 19c, with fins to 50 catch the wind, the swing of the carriers being restricted by stop lugs 6c on the sides 6 of said frame.

In the modified construction illustrated in Figs. 9 and 10, the lens carriers 15d and 16d are arranged to swing on diametrically-arranged vertical axis pivots 13d and 14d 55 within the frame 1 and are provided at one of their sides respectively with wind catching fins 19d and 20d, their swing being limited as in the embodiment of Figs. 7 and 8 by stop lugs 6d on the sides 6 of the frame 1.

In the alternative embodiment of Figs. 11 and 12, the lens carriers 15e and 16e are arranged to swing on diametrically-arranged horizontal axis pivots 13e and 14e within the frame and respectively have along their bottoms wind catching fins such as instanced at 19e, their swing being limited by stop lugs 9e and 10e respectively 60 on the top bar 9 of the frame and on the cross bar 10.

Having thus described my invention, I claim:

1. A warning signal device for use on highways comprising a combination including an open frame, support means supporting said open frame in an upright position, 70 a plate-like lens carrier, pivot means freely suspending the lens carrier within said open frame, said pivot means including a pivot pin supported from said open frame

and positioned transversely of the plane of said frame, a light-reflecting lens mounted in the lens carrier, and fin means extending from said lens carrier for swinging said lens carrier about said pivot pin in response to wind forces to produce oscillations of said lens carrier in the plane of said frame, said frame acting as a stop means to restrict the amplitude of said oscillations.

2. A warning signal device for use on highways comprising a combination including an open frame which includes side portions of predetermined thickness to form a plane therebetween, support means supporting said open frame in an upright position, a plate-like lens carrier, pivot means freely suspending the lens carrier within said open frame, said pivot means including a pivot pin positioned with its axis in said plane and supported from said frame, a light-reflecting lens mounted in the lens carrier, fin means swinging said lens carrier about said pivot pin in response to wind forces to produce oscillations of said lens carrier, and means restricting the amplitude of said oscillations in the direction transverse to said plane thereby creating a flickering light reflection.

3. A warning signal device for use on highways comprising a combination including an open frame of predetermined thickness having side members joined together at their ends by transverse members to form a plane 25 therebetween, support means supporting said open frame in an upright position, said support means including a U-shaped frame hinged at its open end to said open frame so as to fold therewith to form a compact package when closed and so as to open up to form a support, a plate-like lens carrier, pivot means freely suspending the lens

5

carrier within said open frame, said pivot means including a pivot pin positioned with its axis in said plane and supported from said frame, a light-reflecting lens mounted in the lens carrier, fin means swinging said lens carrier about said pivot pin in response to wind forces to produce oscillations of said lens carrier, and means restricting the amplitude of said oscillations in the direction transverse to said plane thereby creating a flickering light reflection.

4. The warning signal device defined in claim 3, wherein in said fin means includes a fin extending from said lens carrier at an angle other than perpendicular to the plane of the lens carrier.

5. The warning signal device defined in claim 3, wherein said means for restricting the amplitude of said oscillations includes stop means formed by said side members.
